UNITED STATES PATENT OFFICE

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK

AEO LIGHT

Application filed May 28, 1927. Serial No. 195,129.

This invention relates to certain new and useful improvements in sources of light for producing a photographic record of electrical variations corresponding to sound wave variations and to the method of producing such sources of light and is a continuation in part of my prior application, Serial No. 719,098, filed June 10th, 1924.

The main object of the invention resides in the method of producing a source of light which varies instantaneously and accurately in accordance with variations in the electric current flowing in a circuit connected across the electrodes of the lamp.

A further object contributing substantially to the above described lamp resides in the particular method of activating the cathode whereby a more effective and stable source of light is produced for the purpose above described.

A further object resides in the production of a source of light which can be used for comparatively long periods of time without decrease in effectiveness.

Other objects and advantages relate to the details of the source of light and method of producing the same, all as will more fully appear from the following description taken in connection with the accompanying drawings, in which:

The three figures are sectional views of the source of light including more or less diagrammatic illustrations of the method of producing the lamp and activating the electrodes thereof.

Generally speaking, the source of light includes a bulb —1— containing a pair of spaced electrodes —2— and —3—. The anode —2— may be formed of a nickel plate and a satisfactory size for the plate is 1/4th of an inch by 1/8th of an inch and .005 of an inch thick.

The cathode —3— may be formed of a platinum wire .0023 of an inch by .011 of an inch and 3/4ths of an inch long. The cathode —3— is preferably in the form of an inverted U and this form seems to be important because the source of light retains its efficiency for longer periods of time than when the cathode is straight, and this seems to result from the

fact that each leg of the U-shaped cathode sputters material from the oxide coating on to the opposite leg, thereby causing a great increase in the life of the material.

The two electrodes are comparatively closely associated and a satisfactory condition is found when the plate —2— is spaced approximately 3/16ths of an inch from the filament or cathode —3—. The U-shaped cathode is attached at its ends to two leads —4— and —5— so that it may be used as a filament and may be heated by the passage of electric current therethrough.

The stem —6— of the bulb —1— projects upwardly a sufficient distance so as to surround the leads and all portions of the cathode —3— that are not coated as hereinafter described, so that only the portions of the cathode which have an oxide coating can glow.

This feature is found important if smooth reproduction is desired because it prevents the glow from running down any uncoated portion of the electrode when the light is modulated.

The platinum strip which constitutes the basic portion of the cathode —3— is preferably twisted, and just before sealing the stem —6— into the shell of the bulb —1—, the exposed portion of the platinum wire is coated with calcium nitrate while a current of 2.9 amperes is flowing through the filament or platinum wire.

This forms a layer of calcium oxide as a protection to the platinum wire. The current flowing through the platinum wire is then increased to 3.1 amperes and a heavy smooth layer of barium nitrate is coated upon the calcium oxide and the hot platinum filament changes the barium nitrate to barium oxide. The stem carrying the leads and the platinum filament adapted to constitute the cathode —3— and also carrying the plate or anode —2— is sealed into the shell of the bulb —1— as rapidly as possible, preferably with a gas oxygen flame, as such a flame seems better than an oxy-hydrogen flame because of the smaller amount of water evolved by the fires and the question of keeping moisture away from the coating of the cathode is important.

because it appears that under the influence of heat and moisture of the sealing flames, there is a certain amount of hydroxides formed.

5 Preferably, a drying material, such as phosphorous-pentoxide is used in the blow tube to keep moisture from the operator's breath from entering the tube or bulb. The tube or bulb is then sealed onto a vacuum pump, as 70
10 for instance by pipe —7— and it is then ready for the process of evacuation and baking.

The vacuum pump is started and an alternating current of one-half ampere is run through the filament or cathode —3— for instance, as illustrated in Figure 1, the leads 80
15 —4— and —5— being shown diagrammatically as connected to a generator —8— of alternating current.

15 The tube is baked at 300 degrees centigrade for about one-half an hour, and then the temperature is raised to about 400 degrees centigrade, and the alternating current flowing through the cathode —3— to about 1 ampere.

20 The temperature during the first half hour 25 of baking is kept at about 300 degrees C. in order that the hydroxides may be decomposed and changed to the oxides slowly. This keeps the coating on the filament smooth. It is found that if the hydroxides are decomposed too quickly the filament or cathode 30
35 —3— becomes rough, making a light that is of lower resistance and more likely to overload, arc, and cause trouble in recording.

35 When the baking process is completed, the oven is removed and the temperature of the filament is brought up to a dull red. This feature of heating the cathode with its oxide coating to a dull red in a high vacuum is of extreme importance in activating the coating 40
45 on the platinum wire of the cathode —3—, and in the production of a cathode of unusual stability, and unusual effectiveness in the production of a constant and uniform light which will vary instantaneously and sharply in accordance with variations in an electric circuit connected between the cathode —3— and the anode —2—.

50 The anode —2— is then connected in circuit with the cathode —3—, such circuit including an alternating current of about 1200 55
60 volts. As illustrated in Figure 2, this alternating current may be evolved from a transformer —9— with two 100-watt lights —10— in series with the primary windings. At the same time a direct current of approximately 2.6 amperes is caused to flow through the cathode —3—, as for instance by a circuit connected to the leads from the ends of the cathode, which circuit includes a source of direct 65
70 current, as battery —11—.

75 This current is allowed to flow until the plate or anode —2— is red hot and the characteristic spectrum of the cathode coating material is produced, or in the case of barium a green glow comes from the filament or

cathode —3—. This step in the process is also important in the production of an effective lamp, as above described, and when this point is reached, the tube or bulb —1— is ready for the admission of an inert gas, 70
75 preferably helium, which has been carefully purified by some agent, such as metallic calcium or magnesium. It is preferable to apply an alternating current of about 1500 volts to the plate filament as a starting 75
80 voltage.

The pump is closed off and helium is admitted to the tube —1— until the desired pressure is reached, at which time a glow will appear on both plate and filament. When such pressure is reached, the current is shifted from alternating current, as above described, to a direct current of about 350 volts with a resistance of about 10,000 ohms in series.

85 As diagrammatically illustrated in Figure 3, the anode and the cathode may be connected in circuit including the desired source of potential, as battery —12—, and the desired resistance —13—, the positive terminal of the battery being attached to the plate and the negative terminal being attached to the filament.

90 This association of elements will cause the filament to glow and if the entire exposed 95 length of the filament is not active, it may be made so by increasing the voltage to about 450 volts for several minutes. The gas pressure is then adjusted to give the correct current reading, and a satisfactory reading is 100 found to be between five to 10 milliamperes on 315 volts with 10,000 ohms in series. The tube is then ready to be sealed off and used.

105 The light of this invention is essentially a cathode glow lamp in which a highly intense negative or cathode glow is concentrated about the cathode, and is separate from the anode glow at operating voltage, and at the gas pressure utilized, and it is this cathode glow that is photographed in the production of a sound record.

110 It is found, however, that when the light is operated the cathode or negative glow includes a helium glow concentrated about the negative electrode and outside of this helium glow there is a green halo which shows the presence of a barium glow in some form, probably either barium metal or barium sub-oxide, and therefore, the light of this invention is not a pure gas discharge light, but shows a combination gas and metal spectrum.

115 It is found that when strontium is used instead of barium the resultant halo surrounding the gas glow is bluish.

120 Altho I prefer barium oxide as the material with which the cathode is to be coated, it is found that other alkaline earth oxides, such as strontium, may be utilized, and altho 125
130

5 I prefer helium as the gas with which the tube is filled, it is found that other inert gases, such as Argon, may be used and for the reason that the particular features of the method here deemed to constitute invention do not relate to the particular gas utilized, or the particular alkaline earth oxide utilized, except in preferred forms, I do not desire to restrict myself to the details of 10 the method or the device described, or the particular materials utilized, or their exact form, except where such details are specifically included in the claims hereto appended.

10 I claim:

15 1. In the method of manufacturing a source of light for producing a photographic record of light wave variations corresponding to sound wave variations, the steps consisting in providing an electrode with an alkaline earth oxide coating, then heating the 20 electrode to a red heat while enclosed in a highly evacuated space, connecting said coated electrode in circuit with a second electrode positioned in said evacuated space and 25 passing an alternating current through said circuit until the coated electrode shows the characteristic spectrum of the coating material.

25 2. In the method of manufacturing a source of light for producing a photographic record of light wave variations corresponding to sound wave variations, the steps consisting in providing an electrode with an electrode with an alkaline earth oxide coating, then heating the electrode to a red heat 30 while enclosed in a highly evacuated space, connecting said coated electrode in circuit with a second electrode positioned in said evacuated space and passing an electric current 35 through said circuit until the characteristic spectrum of the coating material comes from the coated electrode and the other electrode is substantially red hot.

35 3. In the method of manufacturing a source of light for producing a photographic record of light wave variations corresponding to sound wave variations, the steps consisting in providing an electrode with a coating of an alkaline earth oxide and activating said 40 coating by heating the electrode to a red heat while in a vacuous space by the passage of an electric current through the electrode, connecting the coated electrode in circuit with the second electrode positioned in said 45 vacuous space, and passing an alternating current through said circuit until the characteristic spectrum of the coating material comes from the coated electrode.

40 4. In the method of manufacturing a source of light for producing a photographic record of light wave variations corresponding to sound wave variations, the steps consisting in placing two electrodes in a bulb, one of which electrodes has a coating of an 45 alkaline earth oxide, evacuating the bulb,

heating the coated electrode by the passage of an electric current to a red heat, connecting said electrodes in a circuit, and passing a current through said circuit until the characteristic spectrum of the coating material 70 comes from the coated electrode.

5. In the method of manufacturing a source of light for producing a photographic record of light wave variations corresponding to sound wave variations, the steps consisting in placing two electrodes in a bulb, one of which electrodes has a coating of an alkaline earth oxide, evacuating the bulb, heating the coated electrode by the passage of an electric current to a red heat, connecting 75 said electrodes in a circuit while the coated electrode is maintained in a heated condition, and passing a current through said circuit until a glow comes from the coated electrode.

80 6. In the method of manufacturing a source of light for producing a photographic record of light wave variations corresponding to sound wave variations, the steps consisting in placing two electrodes in a bulb, one of which electrodes has a coating of an alkaline earth oxide, evacuating the bulb, heating the coated electrode by the passage of an electric current to a red heat, connecting 85 said electrodes in a circuit while the coated electrode is maintained in a heated condition, and passing a current through said circuit until a glow comes from the coated electrode.

90 7. In the method of manufacturing a source of light producing a photographic record of light wave variations corresponding to sound wave variations, the steps consisting in placing two electrodes in a bulb, one of which electrodes has a coating of an alkaline earth oxide, evacuating the bulb, 95

heating the coated electrode by the passage of an electric current to a red heat, connecting said electrodes in a circuit while the coated electrode is maintained in a heated condition, passing a current through said circuit until a glow comes from the coated electrode, and maintaining the electric current in the circuit between said electrodes 100 until the characteristic spectrum of the coating material comes from the coated electrode.

105 8. In the method of manufacturing a source of light for producing a photographic record of light wave variations, the steps consisting in placing two electrodes in a bulb, one of which electrodes has a coating of an alkaline earth oxide, evacuating the bulb, heating the coated electrode to activate the coating, connecting said electrodes in a circuit and passing a current through said circuit until 110 the characteristic spectrum of the coating 115

material comes from the coated electrode, and admitting an inert gas to the bulb.

9. In the method of manufacturing a source of light for producing a photographic record of light wave variations, the steps consisting in placing two electrodes in a bulb, one of which electrodes has a coating of an alkaline earth oxide, evacuating the bulb, heating the coated electrode to activate the coating, connecting said electrodes in a circuit and passing a current through said circuit until the characteristic spectrum of the coating material comes from the coated electrode, and admitting helium to the bulb.

10. In the method of manufacturing a source of light for producing a photographic record of light wave variations corresponding to sound wave variations, the steps consisting in providing an electrode with an alkaline earth oxide coating, then heating the electrode to a red heat while enclosed in a highly evacuated space, connecting said coated electrode in circuit with a second electrode positioned in said evacuated space, passing an alternating current through said circuit until the coated electrode shows the characteristic spectrum of the coating material, admitting an inert gas to the bulb, and passing a direct current through the circuit connecting the electrodes.

11. In the process of producing a glow lamp comprising coating an electrode with an alkaline earth metal, inserting said electrode and a second electrode in a bulb connecting said coated electrode in circuit with a source of direct current potential and allowing current to flow for a period of time, then connecting a high voltage source of alternating current between the two electrodes and allowing alternating current to flow through the tube while a high vacuum is maintained until the characteristic spectrum of the electrode coating material is observed between the electrodes.

12. In the process of producing a glow lamp comprising coating an electrode with a barium compound, inserting said electrode and a second electrode in a bulb connecting said coated electrode in circuit with a source of direct current potential and allowing current to flow for a period of time, then connecting a high voltage source of alternating current between the two electrodes and allowing alternating current to flow through the tube while a high vacuum is maintained until a green flash is observed between the electrodes.

13. In the process of producing a glow lamp comprising heating an electrode in air and applying first a coating of calcium and then a coating of barium nitrate, inserting said electrodes and a second electrode in a bulb connecting said coated electrode in circuit with a source of direct current potential and allowing current to flow for a period of

time, then connecting a high voltage source of alternating current between the two electrodes and allowing alternating current to flow through the tube while a high vacuum is maintained until a green flash is observed between the electrodes.

In witness whereof I have hereunto set my hand this 21st day of May 1927.

THEODORE WILLARD CASE.
